 corporation of New York

Application August 3, 1934, Serial No. 738,383

10 Claims. (Cl. 176—124)

This invention relates to positive column tubes and to circuit arrangements between the tubes, and particularly to positive column tubes positioned in closely adjacent parallel relation, and to the circuit arrangements connecting tubes so positioned. By placing positive column tubes in closely adjacent parallel relation, increased intensity of illumination has been obtained, or tubes of smaller diameter may be used resulting in a substantial reduction in the current flow through the tubes with substantially the equivalent light intensity of a high current large diameter tube. In addition, a new visual effect is obtained by tubes arranged in accordance with the invention.

Tube fractures, corona and brush discharges, noise and other undesirable effects between closely adjacent tubes occur when a relatively high potential difference exists between adjacent parts of the tubes, or if the tubes are parallel and closely adjacent to each other, then the effects will probably occur throughout the entire length of the tubes. The invention also eliminates these undesirable and injurious effects by a circuit arrangement, thereby providing a practical construction for tubes arranged in closely parallel position.

The principal object of the invention is to obtain high intensity of illumination from positive column tubes, or to obtain intensity of illumination, equivalent to that obtained from a large diameter high current positive column tube, at a substantially reduced current by placing tubes of substantially smaller diameter in closely adjacent parallel arrangement.

Another object of the invention is to take advantage of the high intensity illumination obtainable from positive column tubes of relatively small diameter by positioning groups of tubes and particularly pairs of tubes closely parallel to each other and so connected electrically that the potential or voltage drop in all parallel tubes is in the same direction.

Another object is to devise a positive column tube arrangement utilizing tubes and preferably pairs of tubes in adjacent parallel relation and so connect them together and with a high voltage transformer that the potential drop in each tube of a pair is in the same direction and the potential difference between adjacent tubes and particularly adjacent parallel tubes is not excessive.

A still further object of the invention is to so connect together a plurality of transformers and a plurality of positive column tubes, at least two

of which are in parallel adjacent relation, so that there is substantially no potential difference existing between parallel adjacent tubes.

Other objects of the invention will be more apparent from the following description taken in connection with the accompanying drawings showing the preferred embodiment of the invention, in which:

Figure 1 shows a connection for a plurality of positive column tubes arranged in pairs in which the tubes of each pair are in adjacent parallel relation and the pairs of tubes are in alignment or positioned end to end. The connections between the high voltage transformer and the tubes are such that a minimum potential drop exists between adjacent portions of the parallel tubes and the tubes in adjacent end to end relation.

Figure 2 shows a plurality of pairs of tubes arranged as in Figure 1 and with a single transformer connected in a different manner from that shown in Figure 1 to obtain substantially the same result, namely, a minimum potential difference between adjacent parallel tubes.

Figure 3 shows a third form of the invention utilizing two transformers connected with parallel adjacent tubes in such a manner that the potential difference between the tubes of any pair of parallel adjacent tubes throughout their lengths is zero or substantially zero.

High intensity or brilliancy of illumination is obtainable from positive column tubes by utilizing a large diameter tube, such as 20 millimeters in diameter, and passing a high current therethrough, such as in the neighborhood of 1000 milliamperes, so that a high current density is obtained in the tube. Positive column tubes of small diameter can be utilized in closely adjacent parallel relation to obtain equivalent or substantially equivalent high intensity of illumination or brilliancy, which intensity is obtained at a considerably lower current and hence at a considerably lower power consumption than required with a single large diameter high current tube. Comparable effective intensity or intrinsic brilliancy of illumination is obtainable with the small diameter tubing, such as 8 to 10 millimeters in diameter carrying a current of from 30 to 80 milliamperes, when these tubes are placed in parallel closely adjacent relation. Such small diameter tubes may be spaced from each other, in order to realize the best effect, anywhere between actual contact and a spacing of one-half inch between the tubes. A greater separation between tubes than one-half inch gives good intensity, but not of the same value as the closer spacing range.

referred to. The close spacing of the parallel tubes also creates a new visual or decorative effect in positive column tube illumination and particularly in sign display, principally because 5 of the narrow band or line separating the illuminated column of gas in each tube. The width of this line or band increases as the tubes are spaced farther apart.

Positive column tubes are connected to a transformer having a voltage output in the neighborhood of 15000 volts. The usual electrical connection between widely spaced positive column tubes and the transformer is to connect the ends of the secondary winding of the transformer to 10 the electrodes in adjacent ends of two tubes in end to end relation, such as the electrodes 19 and 24. The remote or far ends of each pair of parallel tubes are connected together, namely the electrodes 18 and 20, and electrodes 25 and 20 15 27 and the electrodes 21 and 26 are also connected to complete the circuit and thereby connect all tubes in series with the secondary winding of the transformer. Such connections of course utilize a minimum length of wire and in 20 fact very short connections are sufficient since the tubes are in closely adjacent relation.

With the circuit connections as described above, a potential difference of one-half of the transformer potential output, or 7500 volts, exists between the near ends of each pair of parallel tubes, namely between the tubes 13 and 14 at the ends carrying the electrodes 19 and 21 and also between the tubes 15 and 16 at the ends adjacent the electrodes 24 and 26. The potential 25 difference or voltage between the adjacent parallel tubes diminishes toward the far ends of each pair of adjacent tubes where the potential difference is zero. Again the potential difference or voltage between the ends of the tubes 30 which are connected to the ends of the secondary winding of the transformer is the entire potential output of the transformer or about 15000 volts. This potential difference would be between electrodes 18 and 24 and the ends of the 35 tubes carrying these electrodes in the electrical connection now used and described above.

As a consequence of such a tube and circuit arrangement or connection, the glass must have a high resistance to electrical strain and fracture, such as pyrex. Transformers customarily used in sign work with tubes arranged as described above have usually a potential output in the neighborhood of 15000 volts and the tubes, connected as described above, will have set up 40 therein static strain which will be followed by noise, a corona or brush discharge and puncture of the glass tube or tubes, resulting in short life 45 of tubes.

The above difficulties have been overcome by 50 a tube and circuit arrangement, three embodiments of which are shown. One form is shown in Figure 1, where there is shown a positive column tube transformer 10, the primary winding 11 of which is connected with a source of commercial 55 electrical energy such as the wires B and C. The secondary winding 12 of the transformer 10 is connected in series with four positive column tubes 13, 14, 15 and 16 in which pairs of parallel adjacent tubes 13, 14 and 15, 16 are positioned in end to end relation to form any desired design. The tubes of each pair are in closely adjacent relation and preferably parallel to each other in order to obtain high intensity of illumination as discussed above. Obviously, the tubes need not be positioned in

straight lines nor need they be straight tubes, but may be positioned end to end and bent to form any desired form, configuration or design.

The series arrangement or connection is obtained by connecting one end of the secondary winding 12 of the transformer 10 to the electrode 18 at the far end of the tube 13 by the wire 17. The electrode 19 at the other or near end of the tube 13 is then electrically connected to the electrode 20 at the far end of the adjacent parallel tube 14 by a connection 22. The electrode 21 at the near end of the tube 14 is then connected to the electrode 24 at the near end of the tube 15 of the other pair of tubes, which tube has its end adjacent to the tube 13 in end to end relation. The electrode 25 at the far end of the tube 15 is then connected by a wire 28 with the electrode 26 in the near end of the parallel adjacent tube 16 which is the tube in adjacent end to end relation with the tube 14. The electrode 27 at the other and far end of the tube 16 is connected through the wire 29 to the other end of the secondary winding 12 of the transformer 10.

As previously stated and described, all of the tubes are connected in series so that the potential drop in each tube is substantially one-quarter of the potential output of the transformer which, for the purposes of illustration, shall be assumed to be 16000 volts. The electrode 18, therefore, has the full potential applied thereto. This means that the potential at the inner or near end of the tube 13, or at the electrode 19, is in the neighborhood of 12000 volts. If it be assumed that there is no potential drop in the connection 22 between electrodes 19 and 20, and as a matter of fact the potential drop in all connections is negligible, the voltage on the electrode 20 at the far or outer end of the tube 14 will be in the neighborhood of 12000 volts. The electrode 21 at the other or inner end of the tube 14 will have a voltage of approximately one-half of the potential output of the transformer 10, or about 8000 volts. The electrode 24 then has substantially the same voltage as the electrode 21 or about one-half of the potential output of the transformer. The electrode 25 at the other or outer end of the tube 15 has a potential thereon of about 4000 volts.

It will be observed, therefore, that in each tube of a group of parallel tubes, such as tubes 13 and 14 and tubes 15 and 16, irrespective of the number of tubes in each group, the potential drop in each respective tube is in the same direction and, in addition thereto, in each group of tubes one end of each tube of the group is connected to the far end of the adjacent parallel tube of the group. In addition, the electrode in the near or inner end of the last tube of one group of parallel tubes, such as the electrode 21 of the tube 14 of one pair, is connected with the electrode at the inner end of the first tube of another group of parallel adjacent tubes with which the last tube is not in end to end relation, such as the electrode 24 of the tube 15. The transformer 10, therefore, has one end of its secondary winding 12 connected to the outer end of one tube of one group or pair of parallel adjacent tubes and the other end of the secondary winding 12 connected to the far or outer end of the last tube of another group or pair of parallel adjacent tubes, which latter tube is not in end to end alignment with the first tube.

It will be observed by noting the potentials at the respective electrode, as indicated on the

drawings, that the potential difference between the tubes 13 and 14 adjacent the electrodes 18 and 20, respectively, is approximately 4000 volts or one-quarter of the output of the transformer.

5 The same potential difference of one-quarter of the output of the transformer exists at the other end of each tube 13, 14, or uniformly at the electrodes 19 and 21 respectively. This means that the potential difference between parallel adjacent tubes throughout the lengths of each tube, such as tubes 13, 14, is in the neighborhood of one-quarter of the transformer output.

10 A comparison of the potentials on the electrodes of the tubes 15 and 16, indicates that the 15 potential drop in this pair of tubes is also in the same direction and that the potential drop between the adjacent parallel tubes throughout their lengths is one-quarter of the potential output of the transformer or about 4000 volts. It 20 will be further noted that the potential difference between adjacent ends of tubes in end to end relation, such as between electrodes 21 and 26 and electrodes 19 and 24, is approximately one-quarter the potential output of the 25 transformer or about 4000 volts. There has been then a substantial reduction in the potential difference between tubes in adjacent parallel relation and in adjacent end to end relation which reduces to a minimum the effects caused by potential differences in adjacent tubes. Any 30 number of pairs or groups of parallel tubes can be connected together following the principle outlined above and thereby further reducing the potential difference between tubes.

35 Similarly, any number of tubes may be positioned in parallel adjacent relation and by connecting one end of one tube to the far end of the adjacent tube, the potential drop in each tube will be in the same direction so that the potential difference between adjacent tubes will be uniform throughout their lengths. The potential difference between adjacent parallel tubes of equal length will be that fraction of the potential output of the transformer determined by 40 the inverse ratio of the number of equal length tubes connected in series with the transformer. If the tubes are not of equal length, the potential difference can be determined by calculating the potential drop per foot of tubing, calculating 45 the potential at any two adjacent points in parallel tubes, and taking the potential difference at these two points.

50 In Figure 2 the tubes 34 and 35 are positioned in parallel adjacent relation and the tubes 36 and 37 are also positioned in parallel adjacent relation with each other and in end to end relation with the first pair of tubes in the same manner as the tubes in Figure 1 are positioned. The 55 transformer 10 in this circuit arrangement, however, is connected differently from that shown in Figure 1, as will be now described. One end of the secondary winding 12 of the transformer 10 is connected by a wire 40 to the electrode 41 at the near or inner end of the positive column tube 34 so that the maximum output of the transformer is applied at this end of the tube. With four tubes connected in series a potential drop through each tube is substantially one-quarter of the transformer output, which again 60 will be assumed to be 16000 volts, so that the electrode 42 at the far or outer end of the tube 34 has a potential in the neighborhood of 12000 volts. The electrode 42 at the far end of the tube 34 is then connected by a wire 43 to the 65 electrode 44 at the near or inner end of the tube

35 which is in adjacent side by side or parallel relation with the tube 34. The electrode 45 at the outer end of the tube 35 has therefore a potential in the neighborhood of 8000 volts.

70 The electrode 45 at the far end of the tube 35 is connected by a wire 48 to the electrode 49 which is at the inner end of the tube 37 of the other pair of parallel adjacent tubes. The potential upon this electrode is substantially the same as that of electrode 45 or in the neighborhood of 8000 volts. The electrical potential on the electrode 50 at the outer end of the tube 37 is, therefore, in the neighborhood of 4000 volts. The electrode 51 at the outer end of the tube 37 is then connected by a wire 51 to the electrode 52 at the near or inner end of the adjacent parallel tube 36 so that this electrode has a potential in the neighborhood of one-quarter of the potential output of the transformer 10. The electrode 53 then at the far end of the tube 20 36 has an electrical potential of zero and is connected by a wire 54 to the other end of the secondary winding 12 of the transformer 10.

25 It will be observed that the potential in the positive column tubes of each pair of tubes decreases in the same direction, and that the potential difference between each tube of each pair is uniform throughout their length or approximately one-quarter of the transformer output. In the connection shown in Figure 2 the potential difference between the electrodes 41 and 52 30 of the tubes 34 and 36 which are in adjacent end to end relation is greater than one-quarter of the potential output of the transformer.

35 A third form of connection or circuit arrangement is shown in Figure 3 utilizing a plurality of groups and particularly pairs of positive column tubes in which the tubes of each group or pair are in parallel adjacent relation or position. In this construction a plurality of transformers 40 are used as will be discussed more fully hereinafter. A first pair of tubes 60, 61 are shown in parallel adjacent relation. These two tubes are positioned in end to end relation with a second pair of tubes, 62, 63 which latter tubes are in 45 adjacent parallel relation. A third pair of tubes 64, 65 which are in parallel adjacent relation with respect to each other may be positioned end to end with respect to the tubes 62 and 63, or may be positioned in any other relation as desired, 50 the pairs or groups, as illustrated, being spaced from each other. A fourth pair of tubes 66, 67 are shown in parallel adjacent relation with respect to each other and in end to end relation with the third pair of tubes 64, 65. All of these 55 pairs of tubes may be arranged so as to produce any desired design.

60 A transformer 71 having a primary winding 71 connected with a source of electrical energy, such as the commercial mains B and C, has one end 65 of the secondary winding 72 connected by a wire 73 to the electrode 90 at one end of the tube 60. The electrode 91 at the other end of the tube 60 is connected by a wire 74 to the adjacent electrode 92 in the adjacent end of the tube 62. The electrode 93 at the other end of the tube 62 is in turn connected by a wire 75 to the electrode 94 in one end of the tube 64 and the electrode 95 at the other end of this latter tube is connected by a wire 76 to the electrode 96 in the adjacent 70 end of the tube 66. The electrode 97 at the other end of the tube 66 is connected by a wire 77 to the other end of the secondary winding 72 of the transformer 70.

75 A second transformer 80 has its primary wind- 75

ing 81 connected with the power mains B and C and one end of the secondary winding 82 is connected by a wire 83 with the electrode 100 at the end of the tube 61. The electrodes 90 and 100 are at adjacent corresponding ends of the parallel tubes 60 and 61 and each is connected with the secondary winding of its respective transformer 10 and 80. These two transformers have substantially the same potential outputs so that the potential drop in each tube is in the same direction and the potential difference throughout the lengths of the tubes 60, 61 is substantially zero. The electrodes 100, 101, 102, 103, 104, 105, 106, 107 of the positive column tubes 61, 63, 65 and 67 are connected together, respectively, by the wires 84, 85 and 86 in the same order or sequence as the tubes 60, 62, 64 and 66 are connected together. The other or last electrode of the tube 66 is connected by a wire 87 to the other end of the secondary winding 82 to complete the circuit connecting all of the tubes 61, 63, 65 and 67 in series with the transformer.

The potential difference between the second pair of parallel adjacent tubes 62, 63 throughout their length is also zero or substantially zero and the potential drop is in the same direction in each tube. The same is true of the third pair of tubes 64, 65 and the fourth pair of tubes 66, 67, the electrodes of which are connected to the other ends of the secondary windings 72 and 82 of their respective transformers 10 and 80 through wires 77 and 87 respectively. It will be noted also that since the connections between tubes have a negligible potential drop there-through, the electrodes of tubes in adjacent end to end relation have substantially the same potential so that the potential difference between tubes in adjacent end to end relation is substantially zero.

With the construction described in Figure 3, a plurality of groups of parallel positive column tubes are provided in which each tube of each group is in adjacent parallel relation and the potential drop throughout the length of each tube of each pair is in the same direction. With the same potential applied at the electrodes at corresponding ends of each group of tubes, there is no or substantially no potential difference between adjacent portions of all the tubes throughout their lengths. It will be observed, therefore, that there is no potential strain exerted upon adjacent glass tubing either in parallel or in end to end relation and that corona and brush discharge effects are entirely eliminated.

It is evident that the transformers need not have the same potential output but may in fact be different so long as an excessive potential difference will not exist between adjacent parallel tubes. As a matter of fact the potential output of the two transformers may vary by 4,000 volts and the potential difference between tubes will not exceed the potential difference existing between the adjacent parallel tubes shown in Figures 1 and 2. The preferred condition, however, is to so select the tube length and potential output of the transformers so that the potential difference between adjacent parallel tubes is substantially zero. It may also be pointed out that the transformers must be connected in the same phase and a simple electric lamp tester can be used and connected across wires 73 and 83 to determine the phase relation. If the test lamp is illuminated the voltage is out of phase and should be corrected so that the test lamp is not

illuminated which indicates that the voltages in both transformers are in phase. It is evident also that the electrodes need not be arranged so that they are adjacent each other but may come at any point between the ends of the adjacent parallel tube.

It is evident, therefore, that improved operation of adjacent parallel tubes is obtained wherever the potential difference throughout the lengths of a group or pair of parallel adjacent tubes is reduced to a minimum as shown in Figures 1 and 2 where the potential difference is substantially that fraction of the potential output of the transformer used as the inverse ratio of the number of tubes connected in series. The potential difference between adjacent parallel tubes may be entirely eliminated with a construction such as shown in Figure 3 where each parallel tube of a group of parallel tubes is connected in series with one tube of the other groups of parallel tubes and a transformer in corresponding relation.

Various modifications will occur to those skilled in the art in the configuration, composition and disposition of the component elements going to make up the invention as a whole, as well as in the selective combination or application of the respective elements, and no limitation is intended by the phraseology of the foregoing description or illustrations in the accompanying drawings.

What is claimed is:

1. A positive column tube arrangement comprising a plurality of groups of positive column tubes in which the tubes of each group are positioned in parallel adjacent relation, a high voltage transformer means, and connections between the high voltage transformer means and the tubes connecting the tubes in series and so that the voltage drop in all adjacent parallel tubes is in the same direction.

2. A positive column tube arrangement comprising a plurality of groups of positive column tubes at least two of which are positioned in parallel adjacent relation, a high voltage transformer means, connections between the high voltage transformer means and the positive column tubes and between the tubes so that one end of one parallel tube is connected to the far end of its adjacent parallel tube.

3. A positive column tube arrangement comprising a plurality of pairs of positive column tubes, the tubes of each pair being positioned in parallel adjacent relation with each other, a high voltage transformer means, connections between the tubes so that the adjacent end of one tube of each pair of parallel tubes is connected to the far end of the other tube of the pair, and connections connecting each pair of tubes in series with another pair and with the transformer.

4. A positive column tube arrangement comprising two pairs of positive column tubes, the tubes of each pair being positioned in parallel adjacent relation, a high voltage transformer, connections between the tubes so that the adjacent end of one tube of each pair of parallel tubes is connected to the far end of the other tube of the pair, and connections connecting each pair of tubes in series with the other pair and with the transformer.

5. A positive column tube arrangement comprising two pairs of positive column tubes, the tubes of each pair being positioned in parallel adjacent relation and each pair of tubes being positioned end to end, a high voltage transformer,

connections between the tubes so that the adjacent end of one tube of each pair of parallel tubes is connected to the far end of the other tube of the pair, a connection connecting each pair of tubes in series with the other pair, and connections connecting the transformer with one tube of each pair at the ends which are adjacent each other.

6. A positive column tube arrangement comprising two pairs of positive column tubes, the tubes of each pair being positioned in parallel adjacent relation and each pair of tubes being positioned end to end, a high voltage transformer, connections between the tubes so that the adjacent end of one tube of each pair of parallel tubes is connected to the far end of the other tube of the pair, a connection between the transformer and the far end of one of the pair of tubes, a connection between the transformer and the far end of the tube on the opposite side of the second pair of tubes, and connections connecting one pair of tubes in series with the other pair.

7. A positive column tube connection comprising pairs of positive column tubes, the tubes of each pair being positioned in parallel adjacent relation and each pair of tubes being positioned end to end, a pair of high voltage transformers, connections connecting one tube of each pair in series with each other and with one of the high voltage transformers, and connections connecting the other tube of each pair of tubes in series with each other and the other transformer and

in the same relation as the first connections were made.

8. A method of operating positive column tubes from a transformer means which tubes are positioned in adjacent parallel relation comprising applying as high a voltage to the end of one of the parallel adjacent tubes as is available from the transformer means, and applying the maximum voltage now available to the adjacent end of the next adjacent parallel tube so that the voltage drop in all parallel tubes is in the same direction.

9. A method of operating positive column tubes from a transformer means which tubes are positioned in groups of adjacent parallel relation and each group is in end to end relation comprising applying as high a voltage to the end of one of the parallel adjacent tubes in each group as is available from the transformer means, applying as high a voltage as is available to the adjacent end of the other adjacent parallel tubes of each group, and applying as high a voltage as is available to the tubes of each group in end to end relation.

10. A positive column tube arrangement comprising a plurality of positive column tubes having at least two tubes positioned in closely adjacent parallel relation, a high voltage transformer means, and connections connecting the tubes together in series with the transformer means so that the potential drop in adjacent tubes is in the same direction.

HRANT ECKNAYAN.
